VITAMIN B₁₂ FACTOR

Konrad Bernhauer and Wilhelm Friedrich, both of Aschaffenburg am Main, Germany, assignors, by mesne assignments, to Merck & Co., Inc., Rahway, N.J., a corporation of New Jersey

Application July 15, 1957, Serial No. 671,880

Claims priority, application Germany August 14, 1953

1 Claim. (Cl. 260—211.5)

The present invention relates to the production and isolation of a therapeutically valuable substance and more particularly to a new vitamin B₁₂ factor and also to the method of separating and differentiating this new vitamin B₁₂ factor from other similar substances.

This application is a continuation-in-part of our co-pending application Serial No. 449,318, filed August 12, 1954, for "New Vitamin B₁₂ Factor," now abandoned.

It is an object of the present invention to provide a new composition of matter which shall herein always be designated as vitamin B₁₂ factor III. This designation is given because of the similarity and relation of the composition of the present invention to the other factors of vitamin B₁₂ and adequate directions for the isolation and identification of the vitamin B₁₂ factor III of the present invention will be given herein.

It is another object of the present invention to provide a method of isolating vitamin B₁₂ factor III from a digested sludge.

It is yet another object of the present invention to provide a method of obtaining crystalline vitamin B₁₂ factor III.

It is a further object of the present invention to provide a method for the chromatographic separation of vitamin B₁₂ factor III from the other vitamin B₁₂ factors.

Other objects and advantages of the present invention will be apparent from a further reading of the specification and the appended claim.

The new chemical compound to which this invention refers is provisionally designated as vitamin B₁₂ factor III. It differs from all similar compounds hitherto known and also from the hitherto known vitamin B₁₂ itself. It is able to permit the growth of the *E. coli* mutant 113-3, of *Lactobacillus leichmannii* 313, and of *Ochromonas malhamensis* (Pringsheim), and has a striking and effective action in the therapeutic treatment of pernicious anemia and other macrocytic anemias.

The compound of the present invention was found to have the structural formula shown in Fig. 3 of the drawing. It will be noted that the compound of the present invention differs from vitamin B₁₂ itself in that while vitamin B₁₂ has a methyl group in each of the 5- and 6-positions of the benzimidazole portion of the compound, the factor III of the present invention has a hydroxyl group in the 5-position and no substituent in the 6-position.

Vitamin B₁₂ factor III of the present invention has been found to be highly effective as an antiperneicous anemia factor and this has been proved by clinical tests such as those described in "Arzneimittel-Forschung" 5,442-446 (1955).

The digested sludge obtainable in the anaerobic digestion of sewage sludge by methane fermentation can be used as the starting material for producing this substance. An aqueous extract is first produced therefrom, and from said extract a concentrate which contains, in addition to other representatives of the vitamin B₁₂ group and other impurities, the new vitamin B₁₂ factor III. The crystal-

2

lized vitamin is obtained by further purification of the concentrate.

The vitamin B₁₂ factor III content in digested sludges of different origins varies considerably. There are digested sludges in which this factor predominates and the other vitamin B₁₂ factors, such as for example factor B, cyanocobalamin, pseudo-vitamin B₁₂ and factor A, occur only in relatively small amounts. Such digested sludges contain about 0.3 mg. per litre of vitamin B₁₂ factor III. In other digested sludges this factor occurs in approximately the same amount as vitamin B₁₂, and in others again it occurs only in smaller amounts. However, it has been possible to obtain vitamin B₁₂ factor III from almost all digested sludges.

15 For the purpose of producing vitamin B₁₂ factor III from digested sludge, the latter is mixed in the condition in which it is available or, if necessary, after dilution with a little water, with a small amount, for example 0.1%, of a water-soluble cyanide or bisulphite or free hydrocyanic acid or SO₂, adjusted to a pH of 5-7, and heated for a short time, for example 20 to 60 minutes, to 70-120° C. The vitamin B₁₂ factor III is thereby released from the links to proteins or peptides and rendered extractable.

20 25 The digested sludge thus "activated" is now centrifuged or filtered for the purpose of separating the solid components. It is often advisable, in order to obtain satisfactory flocculation of the impurities to add a small amount, for example 0.2 to 0.5% of iron (ferric) chloride or aluminum sulphate. The clear filtrate, if it has a 30 temperature of over 25°, is cooled and for the purpose of recovering the vitamin B₁₂ factor III is stirred up with a suitable adsorption medium, such as for example activated charcoal, montmorillonite, and the like. A column 35 may also be filled with a suitable adsorbing medium and the liquid to be treated passed through the column for the purpose of adsorption of the vitamin B₁₂ factor III.

35 After separation of the liquid, the adsorbate is washed with water and thereupon subjected to an elution process, 40 whereby the vitamin B₁₂ factor III passes over again into a liquid phase. Elution can be carried out by stirring the adsorbate, for example activated charcoal, with a suitable elution medium, heating the same, and separating it from the elution medium. The vitamin B₁₂ factor III is thereby concentrated in the elution medium. 45 Elution can of course also be carried out in a column.

45 When using activated charcoal, aqueous ketones and aqueous alcohols are suitable for example as elution medium, e.g. a mixture of 30 parts of water and 70 50 parts of ethanol, or 50 parts of water and 50 parts of isopropanol, or 90 parts of water and 10 parts of n-butanol. The eluate is concentrated in vacuo to a small volume in order to reduce the volume and eliminate the organic solvents. The resulting eluate concentrate contains the vitamin B₁₂ factor III already in a considerable 55 concentration, thus for example in a concentration of 20 to 80 mg. per litre.

55 For the purpose of further purification of the eluate 60 concentrates produced in the above-described manner or for the production of pure crystallized vitamin B₁₂ factor III from the eluate concentrates, various methods can be adopted.

60 In one method the eluate concentrate is saturated with 65 ammonium sulphate. The vitamin B₁₂ factor III is thereby flocculated practically quantitatively together with certain impurities of the protein type. This precipitate, which is generally colored red, is separated from the liquid by means of a centrifuge or suitable filter with the use of a filter aid, such as kieselguhr. The flocculated 70 substance produced in this manner can be dissolved in water and subjected to a further purification process. It

can however also be mixed with the necessary amount of a water binding medium, such as dehydrated sodium sulphate, and thereupon ground. A dry powder is thereby produced which can then be subjected to a percolation process.

Dry methanol or methanol having a low water content (for example containing 5% water), or else a mixture of a phenol and a hydrocarbon, or a halogenated hydrocarbon, such as o-dichloro benzene or trichloroethylene or chloroform with 5 to 20% of p-chlorophenol or 7 to 25% of phenol, etc., or carbon disulphide with a phenol, are suitable for example as percolation liquid. During the percolation, the vitamin B₁₂ factor III, together with other vitamins of the B₁₂ group, is washed out of the column, while most of the impurities remain in the column. This process can also be carried out by stirring up the dry powder with one of the liquids mentioned and separating by means of a centrifuge or a filter.

According to another method, the eluate concentrate is mixed with a suitable salt, for example with 30% of ammonium sulphate, and extracted with a low alcohol or ketone, such as isopropanol or methylethylketone, whereby the vitamin B₁₂ factor III passes over into the organic phase. The extracts produced in this manner can be freed in vacuo from alcohol or ketone and the residue subjected to further purification. The extracts can, however, also be mixed with a suitable hydrocarbon, or better still with a suitable halogenated hydrocarbon, such as trichloroethylene, and shaken out with water, whereby the vitamin B₁₂ factor III passes over into the aqueous phase. After separation of this phase and removal of the organic solvents still dissolved therein in vacuo, this aqueous extract can be subjected to a further purification process.

By another method the eluate concentrate, or any other similar aqueous concentrate, is subjected to a liquid-liquid extraction, the extraction medium used comprising mixtures of hydrocarbons or halogenated hydrocarbons or carbon disulphide with halogenated phenol. The hydrocarbons or halogenated hydrocarbons used may be for example benzene, toluene, chloroform, trichloroethylene, chlorobenzene, o-dichlorobenzene. The halogenated phenols used may for example be m-chlorophenol, p-chlorophenol, halogenated cresols etc. An extraction liquid which is used may, for example, contain 13-25% of p-chlorophenol or 9-20% of m-chlorophenol or 17-28% of 6-chloro-3-cresol, etc.

This extraction can be carried out in separatory funnels, for example in the form of a counter-current distribution, or in an extraction centrifuge. The organic extracts containing the vitamin B₁₂ factor III are washed for the purpose of removing impurities, for example with a dilute solution of sodium bicarbonate or with a phosphate buffer solution of 1-5% strength and of a pH of 7-9, and then with water. The washing water is re-extracted with a small amount of extraction medium containing phenol.

For the purpose of further purification of the red colored phenol-containing mixtures which contain the vitamin B₁₂ factor III, said mixtures are mixed with a small amount, for example 5-15%, of a polar oxygen-containing liquid, such as an alcohol or a ketone, ether, etc., and extracted with water. Through the addition of the polar, oxygen-containing liquid, the distribution coefficient of the vitamin B₁₂ factor III is displaced to such an extent in favor of water that the vitamin can at once be extracted with small volumes of water. Similarly to the preceding purification step, this process entails a substantial concentration and purification of vitamin B₁₂ factor III.

The aqueous extracts produced by the last-described process and containing the vitamin B₁₂ factor III and other B₁₂-like factors are thereupon freed in vacuo from the residues of organic solvents, after which they have

a pure red color. Further purification of these extracts can be carried out successfully only by chromatographic processes. For this purpose, the extracts can be concentrated to dryness in vacuo and thereupon passed to the chromatographic column. It is, however, far more convenient and far less injurious to the vitamin, as well as time-saving, to adopt the following method.

The red colored aqueous extract freed from extraneous solvents is mixed with a small amount, for example 0.5 to 2% of a powdered porous substance, such as kieselguhr, cellulose powder, etc., adjusted to a pH of 2.0 to 4.5, but preferably to a pH of 3.0, and vigorously shaken with a small amount of a phenolic substance, for example 8.0% of phenol or 2.2% of p-chlorophenol or 1.7% of m-chlorophenol or 2.2% of p-cresol or 2.2% of m-cresol, etc., whereby the vitamin B₁₂ factor III and other B₁₂-like factors are deposited on the porous substance as a phenol complex.

Numerous phenols, including those mentioned above, have the property of forming with vitamin B₁₂ factor III and other B₁₂-like factors relatively stable hydrogen bridge complexes, which they do also in an aqueous medium, which are not yet completely saturated in relation to said phenols. These complexes are difficultly soluble in

water and have an oily consistency. When shaken up with a small amount of for example kieselguhr, the oily complex containing the vitamin B₁₂ factor III and other B₁₂-like factors is absorbed by kieselguhr. The kieselguhr powder charged in this manner, which is then deep red in color, rapidly settles at the bottom. This deposit can be separated with the aid of a centrifuge or suction filter, while it is advisable to use, for example, kieselguhr as a filter aid. The red deposit sucked off is thereupon mixed with the necessary amount of acetone, or better still, of a

mixture of acetone and ether, for the purpose of removing the phenolic substance, whereby the latter is dissolved and the vitamin remains on the filter (for example kieselguhr). The deposit free from phenol is now separated, washed with, for example, acetone, and freed from solvent.

The resulting preparation, which is a pure red in color, contains the vitamin B₁₂ factor III and other B₁₂-like compounds in a highly purified condition and can be directly chromatographed for the purpose of further purification.

Since the vitamin B₁₂ factor III is always accompanied in the digested sludge by a number of other vitamin B₁₂ factors, chromatography is a critical and decisive purification step and must be carried out with particular care. An important prerequisite for success of the chromatographic

purification is the maintenance of a defined molecular structure of all vitamin B₁₂ factors during this operation. This condition is best fulfilled by first treating the vitamin B₁₂ mixture to be chromatographed with, for example, gaseous hydrocyanic acid, whereby the vitamin B₁₂ fac-

tors are converted into cyano complexes. In addition, care must be taken that the filling materials of the chromatography column and of the developers are supplied with a corresponding amount of cyanide ions. The vitamin B₁₂ mixture can however also be chromatographed in

the form of thiocyanate complexes; in this case the column and the developer must contain the corresponding anions, such as thiocyanate, etc.

The chromatographic separation of the vitamin B₁₂ factor III from other factors can be carried out by charging the above-described kieselguhr or cellulose preparation, after suitable treatment with, for example, hydrocyanic acid gas, into a chromatographing column prepared with aluminum oxide and acetone, and chromatographing it with a mixture of acetone and water containing, for exam-

ple, cyanide ions. The developer has to contain a $\frac{1}{500}$ to $\frac{1}{50}$ molar cyanide concentration. Development is first effected with an acetone-water mixture containing 5-10% of water, and finally with an acetone-water mixture containing 20 to 30% of water. The violet colored factor B contained in every digested sludge leaves the column first,

followed by vitamin B_{12} and then the vitamin B_{12} factor III of the present invention. Other red-colored factors, if present, then follow. After concentration of the fraction containing the vitamin B_{12} factor III in *vacuo*, this factor can be crystallized.

The chromatographic separation of the vitamin B_{12} factor III from the other vitamin B_{12} factors can be carried out still more successfully if a cellulose column and a mixture of n-butanol and water containing cyanide ions, for example, as developer are used. For the purpose of preparing the column, 50 g. of cellulose powder may be mixed with 500 cc. of n-butanol saturated with water. This mixture should contain at least 0.0025%, for example, of cyanide ions. 20 cc. of water, for example, are then added with vigorous shaking or stirring. It is shaken or stirred until the material is completely homogeneous. After standing for several hours, the cellulose suspension is ready for use. When using cellulose flakes instead of cellulose powder, correspondingly more water-saturated n-butanol must be used, because otherwise the mass will be too thick.

The cellulose suspension prepared in the manner described is then filled in several portions into the chromatographing tube and compressed with the aid of a suitable tamper. The column is then washed with a corresponding amount of developer, consisting for example of water-saturated n-butanol, containing 0.0025 to 0.01% of for example cyanide ions, after which the material to be chromatographed, for example the kieselguhr dry preparation containing the vitamin B_{12} factor III together with other vitamin B_{12} factors, is introduced. The vitamin B_{12} factor III can also be introduced into the column in the form of a liquid concentrate, for example dissolved in water-saturated n-butanol. If the material was supplied as a dry preparation, it is moistened with a little water-saturated n-butanol, and after laying on a filter paper disc it is lightly compressed with the aid of a tamper. By the addition of small amounts of developer, the vitamin B_{12} factors are flushed into the cellulose layer, whereupon the development can begin.

In numerous chromatograms the following R values characteristic of each factor were observed:

Vitamin B_{12} factor:	R values
Factor B	0.40-0.60
Vitamin B_{12}	0.21-0.29
Factor III	0.08-0.12

The fluctuations of the R values are due to the different methods of production of the columns, because it is not possible to carry out this process absolutely identically each time and because of the different amounts of impurities especially of salts. While the relative R values are largely independent of the water content of the column, the absolute R values depend to a great extent on the amount of water stirred in. It is therefore advisable always to stir the same amount of water into the cellulose suspension, namely the amount at which the optimum sharpness of separation of the vitamin B_{12} factors can be achieved.

In less complicated cases, single chromatography will be sufficient for the practically complete separation of the individual vitamin B_{12} factors, because the cellulose-n-butanol column is exceptionally selective. The vitamin B_{12} factor III produced in the above-described manner can thereupon be extracted with water from the solution produced. After suitable concentration and the addition of, for example, acetone, the vitamin B_{12} factor III is crystallized.

The vitamin B_{12} factor III is characterized in the following manner:

It is a red crystalline neutral substance very similar to vitamin B_{12} , containing 55.15% of carbon, 6.27% of hydrogen, 13.71% of nitrogen, 2.24% of phosphorus and after combustion leaving 11.62% of ash, the ash including cobalt as a component (all values refer to the

anhydrous substance dried at 50° in high vacuum). It differs from vitamin B_{12} , however, very sharply through its distribution coefficient in certain pairs of solvents, such as for example in systems consisting of water and mixtures of phenols and chlorinated hydrocarbons. Table I contains a compilation of figures which represent the concentrations of the respective phenols in trichloroethylene, at which the distribution coefficient of the vitamin B_{12} and of vitamin B_{12} factor III is equal to 1. These figures are very characteristic and permit vitamin B_{12} factor III to be differentiated from the known vitamin B_{12} .

TABLE I

Distribution of vitamin B_{12} and vitamin B_{12} factor III between water and trichloroethylene+phenol compound

Phenol compound	Concentration of phenol compound at which the distribution coefficient of the respective vitamin B_{12} factor in the water/trichloroethylene + phenol compound is about 1. Volumetric ratio of the phases 1:1, pH about 7.0			
	Vitamin B_{12}		Vitamin B_{12} Factor III	
	a	b	a	b
m-chlorophenol	5.4	0.42	8.7	0.68
p-chlorophenol	7.7	0.6	12.3	0.98

The novel features which are considered as characteristic for the invention are set forth in particular in the appended claim. The accompanying drawings are however given for the purpose of better understanding of the distinguishing characteristics of the product of the present invention. In the accompanying drawings:

Fig. 1 is a graphic representation of the absorption spectrum of the vitamin B_{12} factor III in water, the dotted line referring to the aquo complex (pH 4.0), the solid line referring to the monocyan complex (pH 6.0), and the dashed line referring to the dicyano complex (pH 10.3);

Fig. 2 illustrates the characteristic curve of the values

for reticulocytes, erythrocytes and haemoglobin in the treatment of a case of pernicious anaemia with 150 gamma of vitamin B_{12} factor III.

TABLE III
U.V. absorption maxima of factor III in water

	$m\mu$	$E^{1\%}$ 1cm.	$m\mu$	$E^{1\%}$ 1cm.	$m\mu$	$E^{1\%}$ 1cm.	$m\mu$	$E^{1\%}$ 1cm.	$m\mu$	$E^{1\%}$ 1cm.
Aquocomplex (pH 4)					351	185	500	58.5	526	61
Monocyanocomplex (pH 6)	278	83	295	106	361	201	518	54.5	550	62.5
Dicyanocomplex (pH 10.3)					368	220	540	65	580	76

As can be seen from Table III, the new vitamin B_{12} factor III differs from all hitherto known vitamin B_{12} factors by the appearance of an absorption band at 295 $m\mu$.

The vitamin B_{12} factor III is electrophoretically neutral in pH ranges from 1.0 to 9.5 and acidic at pH values over about 9.5.

Factor B can be produced from the vitamin B_{12} factor III, in similar manner as it can be produced from vitamin B_{12} according to B. J. Armitage et al., J. Chem. Soc., London, 1953, p. 3849, by the action of concentrated hydrochloric acid at 65° for 5 minutes.

The vitamin B_{12} factor III has a strong microbiological activity against the *E. coli* mutant 113-3, *L. leichmannii* 313 and *Ochromonas malhamensis* (Pringheim).

The vitamin B_{12} factor III has a striking and effective action in the therapeutic treatment of pernicious anaemia and other macrocytic anaemias. As an example of several examinations, a diagram is given in Figure 2 which shows the characteristic curve of the values for reticulocytes, erythrocytes and haemoglobin in the treatment of a case of pernicious anaemia with 150 gamma of vitamin B_{12} factor III. In other cases, a full anti-pernicious effect was achieved by application of only 50 gamma of the same factor.

The following examples are given for illustrative purposes only, the scope of the invention not being limited to the specific details of the examples.

EXAMPLE 1

1000 litres of moist digested sludge having a dry substance content of about 10% and a total content of vitamins of the B_{12} group of 0.5 g. (according to the test with the *E. coli* mutant 113-3) are mixed with a solution of 6 kg. of ferric chloride and 1 kg. of sodium bisulphite, and heated for half an hour to 80° at a pH value of 6-7. After sucking off the sludge with the aid of a vacuum-cell filter, the practically clear filtrate (about 750 litres) is intimately mixed with 7.5 kg. of charcoal under cold conditions. The adsorbate produced by centrifuging is boiled up with a total of 75 litres of a mixture of 10 parts by volume of n-butanol and 90 parts of water in several portions, and filtered in the hot state. The resulting eluate is concentrated to a volume of 5 litres by vacuum distillation. This concentrate now contains 300 mg. of vitamin B_{12} (according to the test with the *E. coli* mutant 113-3) including the vitamin B_{12} factor III.

EXAMPLE 2

50 cc. of an eluate concentrate produced from digested sludge as in Example 1 is mixed with stirring with 29 g. of ammonium sulphate and 0.5 g. of kieselguhr. This moist product of 0.3 g. is mixed with 2.8 g. of anhydrous sodium sulphate and ground to a powder. The concentrate of the vitamins of the B_{12} group converted in this manner into a dry powder is then passed to a small percolator and percolated with 15 cc. of a trichloroethylene-phenol mixture having a phenol content of 15%. The remaining percolator material is now brown in color and the entire vitamin B_{12} activity is 75

contained in the red-colored percolate, from which crystallised vitamin B_{12} factor III can advantageously be produced.

EXAMPLE 3

100 cc. of an eluate concentrate of reddish-brown color and produced from a digested sludge, and which contains 30 gamma of vitamins of the B_{12} group per cc. according to the microbiological test with the *E. coli* mutant 113-3, are brought to a pH of 7 and extracted with 20, 10, and 10 cc. of a solution of 20% strength of p-chlorophenol in trichloroethylene. The dark red extracts are combined and washed once with 10 cc. of a solution of sodium bicarbonate of 5% strength and then washed three times more, each time with 10 cc. of water.

EXAMPLE 4

40 cc. of a solution containing 2.9 mg. of vitamins of the B_{12} group together with various impurities in a mixture which consists of 20% of p-chlorophenol in trichloroethylene and which originates from a purification process of the vitamins of the B_{12} group from digested sludge, are mixed with 4 cc. of n-butanol and shaken out four times, each time with 10 cc. of water. The combined aqueous extracts of an intense red color are washed twice, each time with 10 cc. of n-butanol and 3 times each with 15 cc. of ether. An aqueous solution is obtained which has a red color and which contains 2.8 mg. of vitamins of the B_{12} group (according to the test with the *E. coli* mutant 113-3). The aqueous solution is thereupon freed in vacuo from organic solvents.

EXAMPLE 5

45 11 g. of p-chlorophenol and 5 g. of kieselguhr are added to 500 cc. of a purified aqueous solution containing 25 gamma per cc. (according to the test with the *E. coli* mutant 113-3) of vitamins of B_{12} group. After shaking for 10 minutes, the red, flaky, readily depositable precipitate is filtered off with the aid of a glass sinter suction filter G3, then mixed with a mixture of 50 cc. of ether and 50 cc. of acetone, filtered off, after washed with a little acetone, and freed from acetone in the vacuum exsiccator.

EXAMPLE 6

55 A concentrate of the vitamins of the B_{12} group produced from 20 litres of digested sludge is introduced in the form of a kieselguhr concentrate into an aluminum oxide column prepared from aluminum oxide and acetone (diameter 2.6 cm., height 12 cm.). It is eluted with a developer solution consisting of 90% of acetone and 10% of water and containing $\frac{1}{1000}$ mol of sodium cyanide. The water content is gradually increased to 30%. The factor B is practically completely separated from the other components and leaves the column with a water content of 10-15% in the elution medium in the form of a uniform band. A small amount of cyanocobalamin and finally factor III, which constitutes the bulk of the vitamins of the B_{12} group, follow. 60 After concentration of the fraction containing the vitamin B_{12} factor III to a small volume, the factor III is crystallised after addition of acetone.

EXAMPLE 7

A mixture of vitamin B_{12} factors, produced from 10

litres of digested sludge and pre-purified, deposited on kieselguhr and dried, is introduced into a column which has been made from cellulose powder, n-butanol and water with the addition of the customary amount of sodium cyanide. The diameter of the column is 2.7 cm. and its height 7 cm. After development with water-saturated n-butanol, containing the usual amount of sodium cyanide, the individual vitamin B₁₂ factors are collected in the eluate in a practically completely separated form. The fraction containing the vitamin B₁₂ factor III is thereupon extracted with water, the aqueous extract is concentrated in vacuo, and the residue is crystallized with acetone.

EXAMPLE 8

1000 litres of moist digested sludge having a dry substance content of 8% and a content of vitamins of the B₁₂ group amounting to a total of 420 mg. (according to the test with the *E. coli* mutant 113-3) are diluted with 1000 litres of water, mixed with 1 kg. of sodium cyanide, brought to a pH of 6.5 with 3 litres of hydrochloric acid of 20% strength, thereupon heated to 80° C., and separated from solid constituents with the aid of a centrifuge. The clarified centrifugate is cooled to 20° C. and stirred with 10 kg. of activated charcoal for 30 minutes. The charcoal is separated in the centrifuge and thereupon fractionally eluted with hot ethyl alcohol of 70% strength. 150 litres of eluate are produced, which are concentrated to 10 litres in vacuo. The eluate concentrate is extracted five times, each time with 1000 cc. of a mixture of o-dichlorobenzene and 25% of p-chlorophenol, the combined extracts are washed twice, each time with 500 cc. of a phosphate buffer of a strength of 2% and a pH of 7, and then three times, each time with 500 cc. of distilled water. The washing liquids are combined and re-extracted with a small volume of o-dichlorobenzene-p-chlorophenol mixture. The combined organic red extracts are mixed with 1000 cc. of n-butanol and extracted several times with small amounts of water, whereby the vitamins of the B₁₂ group pass over into the water.

The aqueous extracts are washed with a little ether and then freed in vacuo from residues of organic solvents. Thus 5 litres of an aqueous solution of pure red color are obtained, which contain factor III in addition to other vitamin B₁₂ factors. The aqueous solution is then mixed with 1% of kieselguhr, brought to a pH

5 of 3 with the aid of hydrochloric acid, and after adding 2.3% of p-chlorophenol is vigorously stirred for 20 minutes, whereupon the vitamins of the B₁₂ group are precipitated on the kieselguhr. The flaky red precipitate is sucked off through a layer of kieselguhr, the filter residue is mixed with a mixture of 1 litre of acetone and 1 litre of ether and stirred for a certain time. The red precipitate freed in this manner from p-chlorophenol and containing the vitamins of the B₁₂ group is filtered 10 off, washed with acetone, and dried in vacuo.

The dry precipitate is left overnight in an atmosphere containing hydrocyanic acid, thereupon introduced into a cellulose-n-butanol column (diameter 12 cm., height 12 cm.) and chromatographed with water-saturated n-butanol containing 0.005% of hydrocyanic acid. On 15 development of the chromatogram, numerous red or violet bands appear, the lowermost (violet) of which corresponds to factor B. A faint red band (cyanocobalamin) follows, and finally a very thick red band, representing the factor III. After elution of the factor III, there remain in the middle and at the upper end of the column respectively a few violet bands which correspond to other vitamin B₁₂ factors. The fraction containing the factor III is extracted with water, the aqueous 20 extracts are concentrated in vacuo to a very small volume, and crystallized with acetone. The yield of crystalline product is 150 mg.

Without further analysis, the foregoing will so fully reveal the gist of the present invention that others can 25 by applying current knowledge readily adapt it for various applications without omitting features that, from standpoint of prior art, fairly constitute essential characteristics of the generic or specific aspects of this invention and, therefore, such adaptations should and are 30 intended to be comprehended within the meaning and range of equivalence of the following claim.

What is claimed as new and desired to be secured by Letters Patent is:

As a new composition of matter, vitamin B₁₂ factor 35 III having the structural formula shown in Fig. 3 of the drawing.
